UNITED STATES PATENT OFFICE.

JOHN M. ERICKSON, OF DULUTH, MINNESOTA.

BILL-FILE AND PAPER-HOLDER.

SPECIFICATION forming part of Letters Patent No. 729,301, dated May 26, 1903.

Application filed October 30, 1902. Serial No. 129,441. (No model.)

To all whom it may concern:

Be it known that I, JOHN M. ERICKSON, a citizen of the United States, residing at Duluth, in the county of St. Louis and State of Minnesota, have invented certain new and useful Improvements in Bill-Files and Paper-Holders; and I do declare the following to be a full, clear, and exact description of the invention, such as will enable others skilled in the art to which it appertains to make and use the same.

My invention is an improved bill-file and paper-holder; and it consists in the peculiar construction and combination and arrangement of devices hereinafter described and claimed.

The object of my invention is to provide a cheap and simple article of the class described which may be used either on a desk, table, or show-case without danger of injury thereto and which is also adapted to be hung in a vertical position against a wall or article of furniture.

A further object of my invention is to provide improved retaining means which while preventing any of the papers on the file from becoming accidentally disengaged therefrom permits the ready removal of the papers when the same is desired.

In the accompanying drawings, Figure 1 is a perspective view of an improved bill-file and paper-holder embodying my invention, showing the same in a horizontal position, as when used on a table, desk, or show-case; and Fig. 2 is a side elevation of the same in a vertical position and hung against a wall or other object.

In the embodiment of my invention I provide a base 1, which is here shown as comprising a number of radially-disposed arms 2 and a suspending-arm 3. At the intersection of the said arms at the center of the base is an outwardly or upwardly projecting filing-spur 4, the point of which is sharpened, as at 5, to enable papers to be readily placed thereon. The arm 3 is provided at its outer end with an eye or loop 5', whereby it may be hung from a hook, nail, or peg, as shown in Fig. 2, and an arm 6, which is parallel with 50 the filing-spur, projects outwardly or up-

wardly from the arm 3, near the outer end thereof.

In practice and as here shown the base, including the arms 2 and 3, together with the filing-spur and parallel arms 6, are formed 55 from a single piece of wire, the same being bent appropriately, as shown, and having retaining-coils 7 bent therein at the intersection of the arms 2 3. Furthermore, the eye 5' is bent at the outer end of the arm 3, and 60 its inner side is closed by a coil 8, which is at the base of the parallel arm 6. The latter is formed at its outer or upper end with a retaining-head 9, bent to one side thereof.

On the parallel arm 6 is pivotally and slidably mounted a retaining-hook 10. The latter is here shown as formed of a single piece of wire bent at one end to form pivotal coils 11, which encircle and are adapted to slide and turn on the supporting parallel arm 6, and 70 also bent to form the arm 12 or body of the hook and oppositely-disposed lateral arms 13 14 near the outer end of the hook, between which lateral arms is formed a loop 15 for engagement with the filing-spur. 75

It will be understood that before placing a paper on the file the retaining-hook will be swung to one side and that after the paper has been placed on the spur 4 the hook will have its loop 15 engaged with the said spur, 80 so that the hook will lie upon the mass of papers on the file and retain them in secure position thereon.

From the foregoing description, taken in connection with the accompanying drawings, 85 the construction, operation, and advantages of my invention will be readily apparent, it is thought, without requiring a more extended explanation.

Various changes in the form, proportion, 90 and the minor details of construction may be resorted to without departing from the principle or sacrificing any of the advantages of this invention.

Having thus fully described my invention, 95 what I claim as new, and desire to protect by Letters Patent, is—

1. In a file of the class described, a base having a filing-spur and a supporting-arm, in combination with a retaining device piv- 100

otally and slidably mounted on the said supporting-arm and having a clasp to engage the filing-spur, substantially as described.

2. A file of the class described, comprising 5 a base having a filing-spur and a supporting-arm projecting from one side thereof and a retaining-hook pivotally and slidably supported on the said arm, the said hook having lateral extensions near its free end, and a loop 10 to engage the filing-spur, substantially as described.

3. A file having radially-disposed base-arms 2, a suspending-arm 3, coils 7 at the intersection of said arms, a filing-spur 4 and a supporting-arm 6, all bent from a single piece 15 of wire, and a retaining-hook pivotally and

slidably mounted on said supporting-arm 6 and adapted to engage the filing-spur, substantially as described.

4. A file having a base, a suspending-arm, a 20 filing-spur, and a supporting-arm, all formed from a single piece of metal, and a retaining device pivotally and slidably mounted on the said supporting-arm and adapted to engage the filing-spur, substantially as described. 25

In testimony whereof I have hereunto set my hand in presence of two subscribing witnesses.

JOHN M. ERICKSON.
